UNITED STATES PATENT OFFICE.

WILLIAM ROGERS, OF HARTFORD, CONNECTICUT.

DESIGN FOR A SPOON OR FORK HANDLE.

SPECIFICATION forming part of Design No. 19,212, dated July 16, 1889.

Application filed April 23, 1889. Serial No. 308,337. Term of patent 7 years.

To all whom it may concern:

Be it known that I, WILLIAM ROGERS, a citizen of the United States, residing at Hartford, in the county of Hartford and State of Connecticut, have invented and produced a new and original Design for Spoon and Fork Handles and Like Articles, of which the following is a specification, reference being had to the accompanying drawings, forming part thereof.

Figure 1 represents a face view of a spoon having its handle ornamented in accordance with my design. Fig. 2 is a longitudinal central section of the same.

The leading features of my design consist in the handle having as contour a substantially-uniform but slightly-curved taper from one end to the other, the upper or wide end of the handle terminating in a series of scallops *a*, and within said end and scallops is formed a scroll *b*, consisting of tear-shaped projections having their small ends bent toward one side of the handle, and starting from the curved bottom of said scroll the handle

has a series of grooves *c* and rounded ribs *d*, 25 slightly converging toward one side, as the lowest groove adjacent to the bowl is transversely across the handle. Within the groove *c* is a fine twisted cording *e*, which thus appears to be wrapped around the handle, and 30 has its surface substantially on the same plane as the surface of the rounded ribs *d*. The grooves on the sides of the cording may have dark oxide therein, if desired.

What I claim is—

The design for the handle of a spoon or other article of table flat ware herein shown and described, having as contour a substantially-uniform but slightly-curved taper from one end to the other, scallops at its widest 40 end, with a scroll terminating in said scallops, transverse grooves across the whole length of the handle, and twisted cording in said grooves, as set forth.

WILLIAM ROGERS.
